Filed Oct. 11, 1965, Ser. No. 87,415

Term of patent 14 years

(Cl. D80—8)

FIG. 4

FIG. 1

FIG. 2

FIG. 3

FIG. 1 is a perspective view of a hanger showing my new design;

FIG. 2 is a sectional view taken through 2—2 of FIG. 1;

FIG. 3 is a fragmentary front elevational view of the top left corner thereof; and

FIG. 4 is an enlarged perspective view of the support hook, shown separately to clarify its appearance.

The essential features of my design reside in the portions shown in full lines on the drawing.

I claim:

The ornamental design for a hanger, as shown and described.
